UNITED STATES PATENT OFFICE.

PETER A. NORDQUIST, OF OGDEN, UTAH, ASSIGNOR TO DETACHABLE PLOW SHARE EDGE MANUFACTURING COMPANY, OF OGDEN, UTAH.

DETACHABLE PLOWSHARE EDGE.

1,401,432.

Specification of Letters Patent. Patented Dec. 27, 1921.

Application filed April 29, 1920. Serial No. 377,556.

To all whom it may concern:

Be it known that I, PETER A. NORDQUIST, a citizen of the United States, residing at Ogden, in the county of Weber, State of Utah, have invented a new and useful Detachable Plowshare Edge; and I do hereby declare the following to be a full, clear, and exact description of the invention, such as will enable others skilled in the art to which it appertains to make and use the same.

The invention relates to detachable plow share edges and has for its object to provide a plow share edge wherein the edge is substantially V-shaped in cross section and is provided with a V-shaped groove in its base for the reception of the V-shaped edge of the plow share, said edge having its channel slightly deeper than the gripping surface on the plow share so that the detachable edge may be driven on the plow share and frictionally held thereon by the spring action of the engaging flanges of the removable or detachable edge. Also to improve and simplify the detachable plow share edge shown and described in my Patent No. 1,307,790 dated June 24th, 1919.

A further object is to provide a detachable plow share edge, thereby providing means whereby when an edge becomes dull or worn, the edge may be easily and quickly removed from the plow share edge, so that a new edge may be forced into frictional engagement with the plow share edge.

With the above and other objects in view the invention resides in the combination and arrangement of parts as hereinafter set forth, shown in the drawings described and claimed, it being understood that changes in the precise embodiment of the invention may be made with the scope of what is claimed without departing from the spirit of the invention.

In the drawings:

Figure 1 is a view in perspective of a plow share showing the detachable plow share edge applied thereto.

Fig. 2 is a sectional view taken on line 2—2 of Fig. 1.

Fig. 3 is a plan view of a piece of sheet metal of the proper proportions and thickness for forming the plow share edge.

Fig. 4 is a sectional view taken on the line 4—4 of Fig. 3.

Fig. 5 is a view in perspective showing the sheet metal after having been bent longitudinally upon itself, which is the first step in constructing the plow share edge. 55

Fig. 6 is a view in perspective, showing the sheet metal after having been bent longitudinally upon itself and drawn partially 60 into the shape desired.

Fig. 7 is a detail perspective view of the complete plow share edge in its finished condition and ready to be applied to the share.

Referring to the drawings, the letter *a* 65 designates the plow as a whole, which plow comprises the mold board *b*, the share *c* and the detachable share edge *d*. The share *c* is of the conventional design and construction, but may be varied as desired. The detachable share edge *d* is constructed from a single piece of sheet metal 5 as shown in Fig. 3. This piece of sheet metal in cross section is constructed preferably thicker in its center longitudinally, as shown at 6, 70 than the edge parts 7 so that when the sheet metal is bent longitudinally upon itself, the share edge will have sufficient body and strength to withstand the strain and work and also the wear thereon. Where the sheet 80 metal is designed to be bent longitudinally on itself, the upper face of the sheet may be scored or provided with a longitudinal cut 8, which cut is V-shaped in cross section, to facilitate the bending of the sheet metal on 85 itself. After the metal piece has been bent longitudinally it is subjected to heat, sufficient for welding, shaping and drawing out purposes. The plow share edge, while in this heated condition, is gradually shaped as 90 shown at 9 in Fig. 6 until that portion 9 will assume the finished shape or contour 10 as shown in Fig. 7. While the share edge is being constructed or shaped in this manner, the fold or bend 11 of the share edge is being 95 drawn to a thin edge portion as shown at 12 in Fig. 7, by means of successive percussive blows. After obtaining the thin edge portion 12 the same may be suitably ground or otherwise machined until said edge portion 100 is brought to a sharpened condition, shown at 13 in Fig. 7, which disclosed the finished detachable plow share edge. In constructing the plow share edge by bending the sheet metal longitudinally upon itself the longitudinally V-shaped channel 14 is formed 105

longitudinally of plow share edge and is adapted to receive the V-shaped edge portion 15 of the plow share *c*. The flanges 14^a of the plow share edge are so angled in relation to each other so that when they are forced into engagement with the upper and lower surfaces of the plow share *c* they will frictionally engage and bind on said upper and lower surfaces thereby maintaining the edge on the plow share by the frictional engagement of the flanges 14^a. The V-shaped channel 14 is deeper than the distance of engaging surfaces of the plow share and flanges 14^a as shown at 14^b so that the detachable plow share edge when the flanges 14^a thereof are forced onto the plow share edge, the frictional binding of said flanges 14^a will not be limited by the engagement of the edge 16 of the plow share *c* with the bottom of the V-shaped channel 14.

It will be seen that a detachable plow share edge is provided which may be quickly applied or removed from the edge of a plow share and also one wherein the use of bolts, rivets or pins is eliminated.

The invention having been set forth what is claimed as new and useful is:—

The combination with a plow share edge having a substantially straight portion and an outwardly and forwardly curved portion at its forward end, of a detachable plow edge therefor, said detachable edge comprising a substantially V-shaped bar having a longitudinally disposed V-shaped channel extending throughout the entire length of the detachable edge, the flanges of said detachable edge being so spaced that when the plow edge is forced into the V-shaped channel, said flanges will frictionally engage the upper and lower faces of the plow share so as to hold the detachable edge thereon, the forward end of the detachable edge conforming to the outwardly and forwardly curved portions of the share edge.

In testimony whereof I have signed my name to this specification in the presence of two subscribing witnesses.

PETER A. NORDQUIST.
